UNITED STATES PATENT OFFICE.

FRANK S. BUCK, OF SPRINGFIELD, VERMONT, ASSIGNEE TO FITZ-EMPIRE DOUBLE PIVOT LAST COMPANY, OF AUBURN, MAINE, A CORPORATION OF MAINE.

LAST LATHE.

Application filed June 14, 1919. Serial No. 304,269.

To all whom it may concern:

Be it known that I, FRANK S. BUCK, a citizen of the United States, residing at Springfield, in the county of Windsor and 5 State of Vermont, have invented certain Improvements in Last Lathes, of which the following description, in connection with the accompanying drawings, is a specification, like reference characters on the drawings indicating like parts in the several 10 figures.

This invention relates to machines for the production of irregular objects from a pattern, and is herein disclosed as embodied in a last lathe.

Great difficulty and expense have been caused in the manufacture of lasts prior to the present invention by the failure of the commercially obtainable machines to reproduce accurately those parts of the model having sharp concavities, such, for example, as portions of the heels and insteps in women's lasts. The reason was that the 10-inch model wheel found on these machines would bridge over a sharply concave hollow and reproduce it on a 5-inch radius. The improperly reproduced portions had then to be hollowed out and finished by hand, which entailed inaccuracy and increased expense.

The simple reduction in size of the model wheel and cutter was not possible because, among other reasons, the axes of the work and cutter were thereby brought so close together that the work, for example at the top of the cone, would interfere with the cutter axis and its co-operating elements when the cutter was treating the lower parts of the last.

40 The present invention contemplates the production of a machine having a model wheel of arbitrarily sharp curvature to enable the wheel to reach the bottom of the sharpest concavity to be found on a last— 45 at the same time having a cutting instrumentality which will follow the model wheel without any of the difficulties which had been encountered in previous efforts to solve the problem.

50 I accomplish this result by the construction of a cutting instrumentality which has

no portions in the vicinity of the work extending in the direction of the axis of the work farther than does the model wheel itself. The cutter is therefore capable of 55 maintaining the same relation to the work that the model wheel does to the model, without danger of interference. I preferably arrange the cutter for movement about a physical axis not materially longer than 60 that of the model wheel.

In the illustrated embodiment of the invention the cutter is mounted on an endless belt passing over a wheel or guide near the work, and driven from an instrumentality 65 remote from the work. Thus I am enabled to use a cutter of conveniently small effective diameter without interference between its driving means and the work.

These and other features of the invention 70 comprising various arrangements and combinations of parts will be understood from the following description of a preferred embodiment thereof, selected for purposes of illustration, and shown in the drawings 75 in which,

Fig. 1 is a side elevation of the machine;

Fig. 2 is a detail of the cutting instrumentality;

Fig. 3 is a cross-section on the line 3—3 80 of Fig. 2;

Fig. 4 is a detail of a cutter;

Fig. 5 is a plan showing the relation of the model wheel and cutter instrumentality.

The main frame 10, swing frame 12, 85 model carriage 14, cutter carriage 16, driving mechanism including the drum 18, width grading mechanism 20, and length grading mechanism 22, are all of ordinary Gilman last lathe construction. The model wheel 90 24 is mounted in the usual manner upon the model wheel carriage. The cutter carriage has pedestals 26 extending upwardly and carrying at its top bearings 28 for a shaft 30 upon which are mounted a pulley 32 95 and a sprocket wheel 34 having teeth 36.

The pedestals 26 carry a forwardly extending arm 38 adjustably mounted upon them by means of the screws 40. This arm carries at its forward end a short shaft 42 100 upon which is mounted guide wheel 44, and carries also guides 46 and 48 which are ar-

ranged tangentially between the wheels 44 and 34. A sprocket chain 50 is arranged to run upon these wheels and guides. The sprocket chain is composed of units each 5 comprising two side plates 52 embracing a link 54, as is customary in sprocket chains. Each link 54 has an upstanding lug 56 upon which is bolted a cutter 58 shown as a half-cup having a substantially semi-circular cutting edge 60.

The curvature of the cutter 58 is substantially that of a cross-section of the model wheel made by a plane passing through the axis thereof and the cutter is 15 so shaped that at the time that it is rolling over the wheel 44 its cutting edge 60 is farther from the axis of the shaft 42 than its heel 62 in order to provide proper clearance.

20 A belt 64 passes over the pulley 32 and the drum 18 and drives the shaft 30 in the usual manner as the cutter carriage is driven along the frame. The wheel 44 is so proportioned that the cutting edge 60, as 25 its cutter 58 passes around the wheel, will describe a surface of revolution substantially identical with the periphery of the model wheel. These parts may be made physically as small as is necessary in cutting 30 lasts without sacrificing strength, rigidity and safety in operation. It has been found by experience that a model wheel of three or three and one-half inches in diameter is sufficiently small to reach the bottom portions of any concavities that occur in commercial last cutting, and I have found it 35 quite practicable to construct the apparatus described upon such a curvature.

The wheel 44 and guide 38 together occupy 40 no more thickness than that of the model wheel itself and its attendant parts so that the cutter can be continuously maintained in the same relation to the work as the model wheel to the model. The cutter 45 will therefore go anywhere upon the work that the model wheel will upon the model and it is impossible for a high part of the last to hang up upon some portion of the cutting instrumentality when the cutter itself 50 is operating upon a low portion such as the top of the toe. The great number of cutting edges upon the endless belt or sprocket chain makes the operation of the machine very efficient and the cutting very smooth.

55 Having described my invention, what I claim as new and desire to secure by Letters Patent of the United States is:—

1. In a machine of the class described, 60 model and work holding instrumentalities, a model following instrumentality having a diameter approximately that of a model last, and a cutter instrumentality rotating on an axis substantially parallel to that of the work and having the same effective diameter, 65 neither the cutter instrumentality nor its

supporting mechanism having any parts in the vicinity of the work extending in the direction of the axis of the work to a substantially greater extent than does any corresponding element of the model following instrumentality. 70

2. In a machine of the class described, model and work holding instrumentalities, a model following instrumentality, having a diameter approximately that of a model last, 75 and a cutter instrumentality having the same effective diameter operating upon a spindle parallel to that of the work, said spindle not being substantially longer than the thickness of the effective portion of the model following instrumentality. 80

3. In a machine of the class described, model and work holding instrumentalities, a model following instrumentality, having a diameter approximately that of a model last, 85 and a rotating cutter instrumentality having the same effective diameter, the spindle of the cutting instrumentality being of not substantially greater length than the thickness of the effective portion of the model following instrumentality. 90

4. In a machine of the class described, model and work holding instrumentalities, a model following instrumentality, having a diameter approximately that of a model last, 95 and a flexible cutter instrumentality having metallic cutting edges and having the same effective diameter, and a driving means for the cutter instrumentality lying substantially in the plane of movement of the cutter 100 instrumentality.

5. In a machine of the class described, model and work holding instrumentalities, a model following instrumentality, a flexible cutting instrumentality comprising metallic 105 cutting edges, and a guide constructed and arranged to hold the cutting instrumentality with regard to the work in similar relation to that between the model and the model following instrumentality. 110

6. In a machine of the class described, model and work holding instrumentalities, a model following wheel having approximately the diameter of a model last, an endless belt carrying a work treating means and a 115 guide for holding the means in a path of curvature substantially equal to that of the periphery of the model following instrumentality.

7. In a machine of the class described, 120 model and work holding instrumentalities, a model wheel, an endless flexible cutter carrier arranged to follow an oblong path, one end of the oblong being shaped to correspond to the effective surface of the model wheel and a driving means for the carrier arranged at the other end of the oblong. 125

8. In a machine of the class described, model and work holding instrumentalities, a model wheel, a guide wheel on an axis nor- 130

rnally collinear with the model wheel axis, a model and work holding instrumentalities, a drive wheel and an endless cutter carrying model following guide, and a chain carrying 10 belt running on the guide wheel and drive wheel, the guide wheel and belt being arranged to carry the cutters in a path corresponding to the effective surface of the model wheel.

9. In a machine of the class described,

model following guide, and a chain carrying cutters on its links arranged to run in a path corresponding to the surface of the model following guide.

In testimony whereof I have signed my name to this specification.

FRANK S. BUCK.
